UNITED STATES PATENT OFFICE.

WALTER G. DENN, OF PHILADELPHIA, PENNSYLVANIA.

MERCERIZING APPARATUS.

SPECIFICATION forming part of Letters Patent No. 655,546, dated August 7, 1900.

Application filed November 6, 1899. Serial No. 736,000. (No model.)

To all whom it may concern:

Be it known that I, WALTER G. DENN, a citizen of the United States, residing in Philadelphia, Pennsylvania, have invented certain 5 Improvements in Mercerizing Apparatus, of which the following is a specification.

One object of my invention is to construct a machine for mercerizing skein-yarn that the skeins may be carried first through the mercerizing liquid and then through the wash-water, a further object being to provide for an automatic change in the position of the skeins on their carrying spools or drums while subject to the action of the mercerizing liquid 15 and also while the yarn is being washed, and a still further object is to readily govern the tension upon the skeins and to provide for the automatic taking up of any slack that may be caused therein during the treatment. 20 These objects I attain in the manner herein-after set forth, reference being had to the accompanying drawings, in which—

Figure 1 is a longitudinal sectional view of a mercerizing apparatus constructed in accordance with my invention. Fig. 2 is a transverse section on the line *a a*, Fig. 1; and Figs. 3, 4, and 5 are detached views, on a larger scale, illustrating certain features of construction of the machine which could not be clearly 30 shown in the general views because of the small scale to which the latter are drawn.

The tub 1 is divided into two compartments 2 and 3 by a central transverse partition 4 and an inclined partition 5, the latter being 35 for the purpose of limiting the capacity of the compartment 2, which contains the caustic-soda solution, whereby the mercerizing of the yarn is effected, the object of this construction being to employ as little of said 40 mercerizing liquid as is necessary to effect the proper action upon the yarn as the latter is being carried through the liquid.

To suitable bearings upon the tub or upon the legs of the same are adapted shafts or 45 spindles which carry sprocket-wheels 6, which support a pair of endless chains 7, the sprocket-wheels being so disposed that the chains on entering the compartment 2 of the tub at the top are caused to pass first downward close to 50 the end of said compartment 2 and to a point close to the bottom of the same and then rise

parallel with the inclined partition 5 and pass into the compartment 3, close to one end of the same. The chains then descend to the bottom of said compartment, traverse the 5: same close to the bottom, and rise adjacent to the opposite end of the compartment, from which they pass down to and under the bottom of the tub and thence up to the starting-point at the end of the compartment 2. 6c

Power may be imparted to any one or more of the sprocket-wheel shafts, so as to cause the chains to traverse in the direction intended.

Rigidly secured to the chains and extending from one to the other are a series of cross-bars 7^a, each of which has at one end a bearing for a spindle 8, to which is secured a spool or drum 9, said spindle also having secured to it a star-wheel 10 and having loosely mounted upon it an antifriction-roller 11, and 65 each bar is slotted throughout the greater portion of its length for the reception and guidance of a block 12, which has a projecting spindle 13, upon which is mounted, so as to be free to turn, a spool or drum 14, the block 70 12 being threaded for the reception of a screw-stem 15, the head 16 of said stem bearing upon a coiled spring 17, which is interposed between said head and a shoulder 18 on the bar 7.

On the inclined bottom 5 of the compartment 2 of the tub is a grooved bar 20, one side of said bar throughout a portion of its length having projecting pins 21, and the other side of the bar throughout the remaining portion of its length having similar projecting pins 22. 80

On the bottom of the compartment 3 of the tub is a bar 20, which, however, has projecting pins 22 on but one side.

The operation of the machine is as follows: 90 A skein or skeins of yarn being applied to the spools or drums 9 and 14 of one of the cross-bars 7^a, the tension-screw 15 is manipulated so as to draw the drum 14 away from the drum 9 until the desired amount of 95 tension has been imparted to the skein, this tension being dependent upon the extent to which the coiled spring 17 has been compressed. This operation is repeated in connection with the drums of all of the cross-bars 7^a. As each skein or bunch of skeins is 100 being carried through the compartment 2 of

e tub, the star-wheel 10, carried by the indle 8 of the drum 9, upon which said ein or bunch of skeins is mounted, comes to contact first with the pins 21 and then th the pins 22 of the bar 20. Hence turning movement first in one direction and then the opposite direction is imparted to the um 9, the bearing of the antifriction-roller upon the opposite flange of the bar 20 in ring the engagement of the star-wheel 10 with the pins 21 22. This causes back-and-forth movement of the skeins and insures the ccess of the mercerizing liquid to all portions of each skein, so that the full mercerizing effect upon all portions of the yarn is se-
tired. After leaving the mercerizing solu-
on the skeins are carried through the wash-
ater in the compartment 3 of the tub, the
ums 9 being turned forwardly by reason of
e engagement of the star-wheels 10 with
e pins 22 of the bars 20 in said compart-
ent. The shrinkage of the yarn due to the
tion of the mercerizing solution thereupon
prevented by the tension which is origi-
illy imparted to the skeins, and if during
e washing of the yarn in the compartment
of the tub there is any relaxation or stretch-
g of the yarn beyond the original limits
ch stretch will be automatically taken up
/ reason of the expansion of the spring 17.
fter the yarn emerges from the wash-water
the compartment 3 of the tub the skeins
ay be removed from the drums 9 and 14
eparatory to the application of fresh skeins
reto either at the same end of the tub or
the opposite end of the same, a continuous
eration being thus provided for.

Having thus described my invention, I
aim and desire to secure by Letters Patent—
1. The combination in mercerizing appa-
ratus, of a tub for containing mercerizing liq-
uid, a pair of endless chains passing through
id tub, and laterally separated from each
her, bars extending from chain to chain
id carried thereby, a pair of skein-carrying
ums upon each of said bars, one of said
ums being located near one end of the bar
id the other near the opposite end of the
me, substantially as specified.

2. The combination in mercerizing appa-
ratus, of a tub having two chambers, one for
ntaining mercerizing liquid and the other
containing wash-water, a pair of endless
ains passing first through one chamber of
e tub and then through the other chamber
the same, said chains being laterally sepa-
ated from each other, a series of bars ex-
nding from chain to chain and carried by
id chains, and a pair of skein - carrying
ums mounted upon each of said bars, one
said drums being located near one end of
e bar and the other near the opposite end
the same, substantially as specified.

3. The combination in mercerizing appa-
ratus, of the mercerizing vessel, a pair of lat-
ally-separated endless chains passing there-

through and carrying bars extending from
chain to chain, a series of pairs of skein-car-
rying drums mounted on said bars, one drum
at each end of the bar, means for traversing
the chains so as to carry the pairs of drums
through the mercerizing vessel, and means
for automatically changing the position of the
skeins on said drums while passing through
the vessel, substantially as specified.

4. The combination in mercerizing appa-
ratus, of a mercerizing vessel, an endless car-
rier passing through the same, pairs of drums
mounted on said carrier for the reception of
the skeins to be treated, and means for mov-
ing one of said drums of each pair from and
toward the other so as to impart tension to
the skein or skeins carried thereby, substan-
tially as specified.

5. The combination in mercerizing appa-
ratus, of a mercerizing-tub, an endless carrier
passing through the same, pairs of skein-car-
rying drums mounted upon said endless car-
rier, and means for imparting yielding or
elastic tension to the skeins carried by said
drums, substantially as specified.

6. The combination in mercerizing appa-
ratus, of a mercerizing-tub, an endless-chain
carrier, a cross-bar thereon, a drum mounted
in fixed longitudinal relation to said cross-
bar, and another drum carried by a block
which is adjustable longitudinally on the
cross-bar, substantially as specified.

7. The combination in mercerizing appa-
ratus, of a mercerizing-tub, an endless-chain
carrier, a cross-bar thereon, a drum mounted
in fixed longitudinal relation to said cross-
bar, another drum carried by a block which
is adjustable longitudinally on the cross-bar,
a screw-stem for adjusting said block, and a
spring acting on said screw-stem so as to im-
part its tension to the block, substantially as
specified.

8. The combination in mercerizing appa-
ratus, of a mercerizing or washing tub, an end-
less carrier, a pair of skein-drums mounted
thereon, a toothed wheel carried by the spin-
dle of one of said drums, and an engaging
rack with which said toothed wheel meshes
as the spools are carried forward through the
tub, whereby rotating movement is imparted
to the drum, substantially as specified.

9. The combination in mercerizing appa-
ratus, of a mercerizing or washing tub, an end-
less carrier, a pair of skein-drums mounted
thereon, one of said drums having a spindle
with toothed wheel thereon and oppositely-
disposed racks for engaging with said toothed
wheel as it is carried forward through the
tub, whereby movement first in one direction
and then in the opposite direction is imparted
to the drum, substantially as specified.

10. The combination in mercerizing appa-
ratus, of a mercerizing or washing vessel, an
endless carrier, a pair of skein-drums carried
thereby, one of said drums having a spindle
with toothed wheel thereon, a rack with which

said toothed wheel engages as it is carried forward through the tub, an antifriction-roller on the spindle, and a bar with which said roller engages in order to retain the 5 toothed wheel in mesh with the rack, substantially as specified.

In testimony whereof I have signed my

name to this specification in the presence of two subscribing witnesses.
